UNITED STATES PATENT OFFICE

2,523,663

PENCIL SHARPENER

John S. Milne, Chicago, Ill., assignor to Sears, Roebuck and Co., Chicago, Ill., a corporation of New York

Application October 17, 1945, Serial No. 622,871

1 Claim. (Cl. 120—96)

1

The present invention relates to pencil sharpeners and is more particularly concerned with certain improvements in pencil sharpener design and apparatus for affording the attainment of a streamline, esthetic product which includes adjustment for pencil diameter variations and severability for chaff discharge.

The principal object of the present invention is the attainment of a pencil sharpener structure whose outer contours are gracefully streamlined after the manner of aeronautic tear drop design and yet in which is incorporated all of the mechanical advantages and structural details of adjustability, efficiency in performance and economy of manufacture.

Pencil sharpeners customarily are provided with a system of rotatable cylinder cutters contained within a housing that provides a reservoir for the retention of cuttings or chaff subject to periodic cleanout or disposal. In addition, this class of apparatus, in order to have universal adaptability, must be provided with aperture adjustment so as to appropriately receive and secure various conventional diameters of pencil structures toward the end of achieving more efficient and concentrically accurate cutting operations. Heretofore known mechanisms in which these functionally desirable features have been incorporated possessed considerable irregularity of outline or contour so as to be lacking from an esthetic or artistic viewpoint. The manner in which the desired structures are designed in the present embodiment contributes toward the attainment of a streamlining of the overall structure whereby there is achieved higher standards of esthetic beauty and pleasing symmetry.

For a more comprehensive understanding of the present invention, reference will now be had to the accompanying drawings and to the following detailed specification in which like references designate corresponding parts throughout and in which:

Fig. 1 is a perspective view of a mechanical pencil sharpening apparatus showing the symmetry and esthetic lines of the outer structure such as is afforded by virtue of the mechanical features embodied in the present invention.

Fig. 2 is a side elevation view partially in section of the apparatus featured in Fig. 1 revealing the interior structure.

Fig. 3 is a plan view of the same apparatus having portions broken away in order to reveal interior features of the construction, and

Fig. 4 is a transverse sectional view taken approximately on the line 4—4 of Fig. 2.

2

Fig. 5 is a sectional view taken approximately on line 5—5 of Fig. 2.

The reference numeral 11 indicates generally a pedestal casting, the foot 12 of which is gracefully curved and filleted with the integral vertical post 13, as best indicated in Figs. 1 and 2. With the latter there is integrally associated at its uppermost extremity a journal ring 14, the outer lines of which form part of the bullet nose or streamline conformation completed in the adjacent threaded collar 15 of the crank arm 16. The journal or bearing ring 14 is centrally apertured as at 17 to receive the principal or bearing portion of a shaft 18 which is confined endwise between the abutment of its enlarged diameter head 19 and the limit shoulder 21 of the threaded collar 15.

A reduced diameter of shaft 18 is threaded as at 22 into the collar 15 so that when the latter is drawn taut, its shoulder 21 engaging the adjacent end surfaces of the bearing portion 18, adequate clearance will be afforded for the easy turning of the assembly with minimum endwise play or clearance. The rotor, which is integral with the head 19, includes a convention cage casting comprising the fore portion 23 having a concentric opening large enough to receive the maximum diameter of pencil and the pair of supporting flanges 24 and 25 within which are received the ends of the cutter shafts after the manner of conventional structure of this class of apparatus. The two shafts converge toward the rotor axis and are threaded into the head 19 giving support each to an associated one of a pair of cutters 26 and 27.

The latter elements are preferably of a cylindrical mill cutter type having spirally fluted cutting edges and integrally formed with beveled gear elements 28 and 29 spaced from each other but meshing with an internally toothed gear ring 31 which may be milled of flat stock material and secured to the forward face 32 of the bearing ring 14. Upon rotation of the manual knob 33 and the arm 16, the entire assembly including the rotor cage 23, shaft 18 and threaded arm nut 15 will revolve customarily in a counter-clockwise direction, as viewed in Fig. 4, and through the engagement of the bevel gears 28 and 29 with ring gear 31 each of the cutters 26 and 27 will describe clockwise rotation about its axis, as viewed.

The forward extremity of the journal ring 14 is reduced in diameter as designated at 35 to afford a facet for thereat receiving an alternatively placeable hood or canopy generally desig-

nated 36 with which is integrally formed a ring 37 adapted to fit the shouldered portion 35 either in the manner designated in Figs. 1, 2 and 3 or optionally at 90° therefrom in the case of wall or vertical surface mounting of the pedestal 11. Toward this end the shoulder 35 may have a pair of peripheral notches 68 and 69 and the fitting ring 37 may have a lug 67 insertable endwise into alternative ones of said notches, see Fig. 5. After the end ring 37 is placed upon the shoulder or undercut 35 and the internally toothed gear ring 31 is positioned and secured, the hood 36 may not be removed inadvertently and the entire assembly including the hood 36 will form an integral association. The hood 36 which overlies the rotor assembly continues the outer streamline symmetry described above in connection with bushing or sleeve 14 and nut 15 and describes substantially 180° of barrel shaped contour terminating at horizontal extremities in the curved edges 41, of which one is visible in Fig. 1 and another in Fig. 3, while just beneath these edges 41 the hood is provided with grooved guide flanges including the protruding lips 42 and the groove recess 43, Fig. 1.

The forward face of the hood 36 is molded so as to present three alternative notches designated 44, 45 and 46 into one or another of which there may be received a detent embossment 47, Fig. 4, of an escutcheon lever 48 which is pivotally supported at 49 on a shoulder screw 51 threaded into the body of the receptacle casting 52. The escutcheon lever 48 includes an arcuate segment 53 having three openings designated 54, 55 and 56 of different diameters each for receiving an appropriate one of three conventional pencil sizes when the lever 48 is characteristically placed, Fig. 4, in corresponding position, which position is detentably retained by the engagement of the ridge embossment 47 within one of the notches 44, 45 or 46.

The receptacle casting 52 affords a chamber 61 for catching and retaining pencil shavings as they fall from the cutter elements 26 and 27 and its side walls 62 are provided with guide lips 63 and grooves 64 on opposite sides to slide into the cooperating lug and groove portions 42 and 43 of the hood 36.

The fore portion of the casting 52 is rounded to complete the streamline contour, as best designated in Figs. 1 and 3, and is provided with a pencil guide opening, as at 65, of maximum diameter formed within the solid top section 66 into the lower extremity of which the pivot screw 51 is threaded. It is to be understood that for the sake of lightness or metal conservation the por-

tion 66 may be hollowed out in those regions where rigidity and strength are otherwise adequate.

While the present invention has been explained and described with reference to a particular structural embodiment, it is to be understood nevertheless that various modifications and variations may be instituted without departing from the essential spirit or scope thereof. Accordingly, it is not intended to be limited to the particulars of the foregoing detailed specification, nor to the illustrations in the accompanying drawings, but rather to be permitted a realm of construction as indicated by the hereunto appended claim.

The invention claimed is:

A pencil sharpener assembly of the rotatable milling-cutter class comprising a pedestal casting formed with a journal for affording bearing support to the shaft of a milling-cutter cage and a foremost shouldered portion affording a ring gear face, a ring gear secured to said face having an internal circle of gear teeth and having an outer diameter marginally greater than that of said shouldered portion, an alternatively positionable hood of partial cylindrical curvatures having a collar portion confined on said shouldered portion and retained thereat by said ring gear, said hood including side elements having parallel guide grooves, a set of pencil pointing milling cutters and supporting cage associated with a shaft rotatable in said pedestal journal, and a shavings receptacle comprising a unitary housing contoured to supplement and continue the curvatures of said hood and having lips receivable in said guide grooves of said hood, said receptacle including a solid foremost section provided with a cylindrical aperture to receive and support pencils directed to the milling cutters of said cage.

JOHN S. MILNE.
